LINER CLAMP FOR PANEL FORM WALLS

George B. Bosco, Chicago, Ill.

Application December 13, 1937, Serial No. 179,383

7 Claims. (Cl. 24—68)

This invention relates to the general art of forms used in the erection of concrete walls, columns and the like, and more especially to forms of the well known type wherein the side and end walls of the form are built up of a series of rectangular panels united edge to edge.

In form walls of this type the panels are provided with rectangular bounding frames that project outwardly from the plane of the panel facing, and adjacent limbs of adjacent frames are temporarily bonded together by removable clamps of various sorts. To stiffen and strengthen the wall to resist the lateral thrust of the wet concrete it is common to employ on the outer side of the wall spaced horizontal and vertical timbers known as liners, and these liners are bonded to each other at their points of intersections by clamps of various sorts, one known form of clamp, illustrated in my former Patent No. 1,682,658, August 28, 1928, consisting of a generally U-shaped member embracing the two liners, and a wedge-shaped block co-acting with said member to tension the same. Somewhat similar clamps consisting of U-shaped rods or wires have been employed for separately bonding the horizontal and vertical liners to the panel frames, as shown, for example, in patent to Anderson, No. 1,970,547, August 21, 1934.

Among the objects of this invention are, to provide an improved clamp that, in slightly different forms, may be used either with wall panels having wooden frames or with wall panels having angle iron frames to bond the horizontal liners to said frames, and may also be used to bond the horizontal and vertical liners at their points of intersection; to provide a clamp of very simple and inexpensive construction; to provide a clamp having tension applying means adjustable to small irregularities or variations in the thickness of the liners; to provide a clamp that, when applied, will stay put in its tensioned position and condition and cannot yield or slip; and, generally, to provide a better clamp for the purposes above mentioned than has heretofore been known.

Approved embodiments of the invention are illustrated in the accompanying drawings, in which—

Fig. 1 is a perspective elevation of a panel-type form wall employing panels having wooden bounding frames and vertical and longitudinal liners or stringers, and equipped with my improved form liner clamps.

Fig. 2 is an enlarged fragmentary horizontal section taken on the line 2—2 of Figs. 1 and 3.

Fig. 3 is a front elevation as viewed from the bottom of Fig. 2.

Fig. 4 is a perspective detail of the form of clamp shown in Figs. 2 and 3 and in part in Fig. 1.

Fig. 5 is a fragmentary perspective detail showing edgewise adjacent panels employing angle iron bounding frames, a horizontal liner, and a form of clamp for bonding the liner to adjacent limbs of the bounding frames and also bonding said limbs to each other.

Fig. 6 is a fragmentary elevation as viewed from the left of Fig. 5 with the liner in transverse section.

Fig. 7 is an isolated detail in top plan view of the clamp shown in Figs. 5 and 6.

I will first describe the form of the invention illustrated in Figs. 5, 6 and 7, since the liner bonding clamp shown therein is somewhat simpler than that illustrated in Figs. 2, 3 and 4. Fig. 5 illustrates a pair of edgewise adjacent wall panels each comprising a multiple ply or laminated facing 10 and an angle iron bounding frame comprising horizontal limbs 11 and vertical limbs 12. The vertical limbs 12 of the bounding frames of adjacent panels lie in contact with each other and are formed with upper and lower registering holes 13 and 14. Extending across the bounding frames of the panels between the pairs of registering holes 13 and 14 is a horizontal liner 15.

The clamp which binds the liner to the bounding frames comprises a generally U-shaped member preferably made as a rod bent to include parallel legs or limbs 16 and an oblique bight 17 portion 11. The free ends of the legs 16 are bent laterally in the form of hooks 18 which extend through the two pairs of registering holes 13 and 14. Attached to one side of the U-shaped member as by spot welding indicated at 19 is a plate 20 formed with a laterally offset intermediate portion 21 having an oblique outer edge that forms a wedge-shaped recess open on its inner side. Cooperating with this recess is a narrow wedge block 22 which is adapted to be driven through the recess, with its inner edge 22' in sliding contact with the outer edge of the liner 15. With the hooks 18 engaged in the holes 13 and 14 of the panel frame members, it is manifest that the driving of the wedge 22 creates a longitudinal tension on the legs 16 of the clamp that causes the wedge to force the liner snugly against the panel frames.

In order to prevent the wedge 22 from working upwardly and becoming loose in its socket, I cut

away an inner portion of the socket wall 21 along the line 23, thus providing an opening through which a nail may be driven obliquely through the wedge and into the liner. To facilitate this, I preferably provide the inner edge of the wedge with vertically spaced notches 24, through any of which a nail 25 may be driven into the liner, the nail being preferably driven only part way, as shown in Fig. 6, to facilitate its easy extraction later when taking down the form. The plurality of notches 24 provides for slight irregularities or variations in the thickness of the liner 15.

From the foregoing it will be seen that the above described clamp not only binds the liner to the frames of the panels but, by reason of the curved form of the hooks 18, the latter also securely bond the adjacent limbs of adjacent frames to each other.

Substantially the same above described form 20 of clamp is used to bond together vertical and horizontal liners at their points of intersection. Referring to Fig. 1, 28 designates vertical liners which intersect the horizontal liners 15 on the outer sides of the latter, and for bonding these 25 liners at their intersections a clamp such as shown in Figs. 6 and 7 but with slightly longer hooks 18' is employed in a horizontal position, the hooks 18' being entered through a pair of holes in the liner 15 on opposite sides of the vertical liner 28. When the wedge 22 is driven home, the two intersecting liners are manifestly securely locked together.

Referring now to Figs. 1 to 4 inclusive, wherein I have shown the panels equipped with wooden 30 bounding frames 27 disposed edge to edge, I employ, for bonding the horizontal liners 15 thereto, a modified form of clamp shown in perspective detail in Fig. 4. This clamp employs the same U-shaped member with attached socket 35 plate 20 for the wedge 22 as described in connection with Figs. 5 to 7. But instead of the hooks 18, or 18', the free ends of the limbs 16 are formed with extensions preferably at right angles with the limbs 16 in the form of upper and lower narrow loops 28 and 29 each formed by doubling the rod or wire on itself and preferably spot welding the end to the base of the extension as indicated at 30 in Fig. 2. The loop-shaped extension 28 is somewhat longer than the extension 29, and both 40 extensions enter registering holes 31 in the adjacent limbs of the panel frames 27, and project some distance beyond said holes, as clearly shown in Fig. 2. A wedge 32 is driven downwardly through the projecting portions of these loop-shaped extensions 28 and 29, the vertical edge of the wedge having a bearing on the adjacent side of one of the frame members 27. And since the main limbs 16 of the clamp hug the opposite edge of the other frame member, not only is the 45 clamp securely anchored at its inner end in the frame members, but the latter are securely bonded together by the wedge 32 in cooperation with the extensions 28 and 29.

In Figs. 1, 2 and 3 I have shown the adjacent 50 vertical limbs of the frame 27 as slightly spaced from each other by a narrow spacer strip 33 attached by tacks 34 to the facing 10 and the inner edge portion of one of the frame members 27. The spacing permits the passage between 55 the limbs 27 of a rod, strap or other member that ties together the two opposed walls of the form; and the spacing strip provides a tight joint at the facing of the two panels preventing concrete working into the joint; the spacer being apertured 60 for the passage of the tie members.

I have herein shown the wedge blocks 22 and 32 as equipped on their lower, narrow ends with a foot 35, the use of which is optional. Where the parts of the clamp are pre-assembled, as will usually be the case, the foot 35 prevents the accidental disengagement of the wedge from its recess or socket during handling of the clamp member.

Variations and modifications of the specific structures shown and described may be resorted 10 to within the scope of the claims.

I claim:

1. A form liner clamp, comprising a U-shaped member adapted to straddle a liner and having anchoring means on the free ends of its two legs, 15 a socket member rigidly secured to and crosswise of the two legs of said U-shaped member at the bight end of the latter and having a wedge-shaped recess, and a wedge adapted to be driven into said recess in engaging relation with said 20 socket member, with an edge of said wedge adapted to bear on said liner.

2. A form liner clamp, comprising a rod bent to form a U-shaped member adapted to straddle a liner, said member having anchoring means on 25 the free ends of its two legs, a socket member comprising a plate rigidly secured to and crosswise of the two legs of said U-shaped member at the bight end of the latter and having its intermediate portion laterally offset to form a wedge 30 shaped recess, and a wedge adapted to be driven into said recess in engaging relation with said socket member, with an edge of said wedge adapted to bear on said liner.

3. A form liner clamp as defined in claim 1, 35 wherein the outer wall of the recess is partially cut away to expose a portion of the wedge for the entrance of a nail to lock the wedge to the liner.

4. A form liner clamp as defined in claim 1, 40 wherein the outer wall of the recess is partially cut away to expose an inner longitudinal edge portion of the wedge, and said inner edge portion has vertically spaced notches for the reception of a nail to be driven into the liner.

5. A clamp for bonding together vertical and 45 horizontal liners of a form wall at their intersection, comprising a U-shaped yoke adapted to straddle one of said liners, the legs of said yoke being long enough to extend partly across the other liner and having on their free ends hooks 50 adapted to enter holes in said other liner, a socket member having a wedge-shaped recess secured to one side of the closed end of said yoke, and a wedge adapted to be driven into said recess in engaging relation with said socket member 55 with an edge of said wedge adapted to bear on said first named liner.

6. A clamp for bonding a liner of a form wall to a pair of adjacent limbs of adjacent panel frames and for bonding together said adjacent limbs, 60 comprising a U-shaped yoke adapted to straddle said liner and having on the free ends of its legs rectangular extensions in the form of narrow loops adapted to extend through and at their outer closed ends project beyond registering holes in said adjacent limbs, one of the projecting portions of said loops being longer than the other, a socket member having a wedge-shaped recess secured to one side of the closed end of said yoke, 70 a wedge adapted to be driven into said recess in engaging relation with said socket member with an edge of said wedge adapted to bear on said liner, and a wedge adapted to be driven through the projecting portions of said narrow loop ex- 75

tensions with an edge of said last named wedge adapted to bear on a side of one of said adjacent limbs of the panel frames.

7. A form liner clamp, comprising a rod bent to form a U-shaped member adapted to straddle a liner, said member having anchoring means on the free ends of its two legs and an oblique bight connecting the other ends of said legs, a socket member comprising a plate welded to one side of said legs and bight and having its intermediate

portion laterally offset to form a wedge-shaped recess, and a wedge adapted to be driven into said recess in engaging relation with said socket member, with an edge of said wedge adapted to bear on said liner, the portion of said plate forming the outer wall of said recess being partially cut away to expose an inner edge portion of the wedge for the entrance of a nail to lock the wedge to the liner.

GEORGE B. BOSCO. 10
